Inventor,

Mortimer L. Smith

UNITED STATES PATENT OFFICE.

MORTIMER L. SMITH, OF DETROIT, MICHIGAN, ASSIGNOR TO JAMES W. TUFTS, OF MEDFORD, MASSACHUSETTS.

DESIGN FOR CASING OF SODA-WATER APPARATUS.

Specification forming part of Design No. 7,143, dated January 27, 1874; application filed December 15, 1873.
[Term of Patent 14 years.]

To all whom it may concern:

Be it known that I, MORTIMER L. SMITH, of Detroit, in the county of Wayne and State of Michigan, have invented and produced a new and original Design for the Casing of a Soda-Water Apparatus, of which the following is a full, clear, and exact description, reference being had to the accompanying photograph making part of this specification:

In the photograph, A represents the lower or main portion of the casing of a soda-water apparatus, which is of rectangular form in cross-section. The upper portion B is shaped to resemble a "Gambrel roof" being inclined on both sides from *a* to *b* and from *b* to *c*. From the center of the roof B on each side projects a gable, C, of corresponding form, the whole being surmounted by a cupola, D, which may,

however, be omitted, if desired, the design thus produced being unique and ornamental. If desired, the casing may be constructed with one gable only, (on the front side,) instead of with two, as above described.

What I claim as my invention, and desire to secure by Letters Patent, is—

The design for the casing of a soda-water apparatus, consisting of the rectangular portion A with its gambrel roof B, having a gable, C, on each side, substantially as herein shown and described.

Witness my hand this 8th day of December, A. D. 1873.

MORTIMER L. SMITH.

In presence of—

JAMES A. RANDALL.
ALBERT E. FRENCH.
